WATERTIGHT CIGARETTE AND MATCH
CASE

Elmer Clampitt, Indianapolis, Ind.

Application May 25, 1949, Serial No. 95,329

1 Claim. (Cl. 224—26)

1

This invention relates to a water-tight case for swimmers.

Many swimmers desire to carry with them certain personal articles, such as cigarettes, matches, lipstick, cosmetics, and similar articles, while actually in the water.

A primary purpose of this invention is to provide for carrying such articles, a water-tight case which can be securely attached to the belt or the top of the bathing trunks of a swimmer.

A further important object of the invention is to provide a water-tight case having a false bottom which can be raised to make the contents more easily accessible.

A further important object of the invention is to provide a water-tight case whereupon opening of the cover releases pin members of the case from the belt while the case hangs therefrom, and at the same time raises the false bottom in the case to make the contents more readily accessible.

A further important object of the invention is to provide a water-tight case incorporating the above indicated objects, which can be easily and economically manufactured.

Further objects and advantages of the invention will become apparent to those versed in the art from the following description of one particular form of the invention designed to carry matches and cigarettes as illustrated in the accompanying drawing, in which

Fig. 1 is a view in front elevation of a case embodying the invention attached to a belt, part of the case being broken away to more clearly show the interior thereof;

Fig. 2 is a view in section on the line 2—2 in Fig. 1;

Fig. 3 is a view in side elevation of the case and belt shown in Fig. 1;

Fig. 4 is a plan view of the case and belt with the cover in open position;

Fig. 5 is a view in section on the line 5—5 in Fig. 1;

Fig. 6 is a view in front elevation of the case and belt with matches and cigarettes therein with the cover rotated 180 degrees in a clockwise direction from the position in Fig. 1;

Fig. 7 is a view in rear elevation of the top portion of the case; and

Fig. 8 is a view in detail in vertical section on an enlarged scale of the false bottom lifting means.

The same reference characters refer to corresponding parts throughout the several views.

A container 10 is integrally formed with paral-

2

lel front and back walls 11 and 12 spaced a sufficient distance apart for a cigarette to be easily slidable therebetween and semi-cylindrical end walls 13 and 14. These walls are of slightly greater height than the length of a cigarette to be carried by the case. Solid cylindrical pillars 15 and 16 reinforce the end walls 13 and 14 which are spaced apart to receive a plurality of cigarettes 44 therebetween in a single row between the walls 11 and 12. The bottom 17 is flat and at right angles to the elements forming the side walls. The container 10 terminates by an open top end 18 in a plane parallel to the bottom 17.

Screw-threaded, vertical studs 19 and 20 are embedded by their lower ends in the tops of the cylindrical pillars 15 and 16 respectively and axially aligned therewith. Nuts 21 and 22 are screw-threadedly engaged on said studs 19 and 20 to move up and down thereon.

A cover 23 is formed to fit over the top 18 of the container 10, including the tops of pillars 15 and 16. An eye 24 in one end of the cover 23 fits over the stud 19 so that the cover 23 is revoluble in a horizontal plane around and slideable up and down said stud 19. A hook 25 is formed in the other end of the cover 23 to fit around the stud 20 when the cover 23 is revolved to a closed position. Two horizontally disposed pins 26 and 27 are embedded in the rear edge portion 28 of the cover 23 to extend at right angles therefrom.

An elastic gasket 29 such as rubber, is formed to fit on the underside of the cover 23 with the exception of the hook 25. The gasket 29 is fixed to the cover 23, and is further secured thereto by a plate 50 which is secured to the cover 23 by screws 30 and 31. This plate 50, which is centered on the bottom of the cover 23, has the same contour as, but is slightly smaller in area than, the horizontal cross-sectional area of the interior of the container 10. The under, exposed side of the plate 50 is roughened, such as by knurling, to provide a match striking surface.

While a gasket is generally more economical, its use can be eliminated by careful finishing of the connecting surfaces between the cover 23 and the container 10.

A belt attaching hook 32 is secured on the back wall 12 of the container 10 with a loop 33 extending above the top 18 of the container 10. Holes 34 and 36, in the front arm and 35 and 37 in the back arm of the belt hook are aligned to receive the pins 26 and 27 when the cover 23 is positioned over the opening 18.

A vertical partition member 38 is slideable in

the vertical grooves 39 and 40 provided in the front and back walls 11 and 12 respectively of the container 10, to have the member guided freely in vertical travel spaced from the end wall 13. A flat horizontal false bottom 41 extends to the left from the bottom of the partition member 38. This false bottom 41 substantially fills the horizontal cross-section of the container 10 to the left of the partition 38 but is free to be moved vertically between side walls of the container 10.

A second false bottom 42 extends horizontally from the partition 38 toward the end wall 13 from a position on the partition at a distance from the top of the partition slightly greater than the length of a match. This horizontal false bottom 42 substantially fills the horizontal cross-section of the container 10 to the right of the partition 38 to be free to shift vertically between the side walls of the container 10.

A string 43 is attached to the bottom of the cover at a distance from the stud 19 approximately equal to the distance of the partition 38 therefrom. The opposite end of string 43 is fixed to the partition approximately midway between the ends of said partition. The length of the string 43 is about two thirds the length of the vertical partition 38.

In use, cigarettes 44 are placed on ends in the major compartment 45 and matches 46 are placed on end in the minor compartment 47. The cover 23 is revolved sufficiently toward an open position so that the pins 26 and 27 are withheld from the holes 34 and 35, and 36 and 37. The belt hook 32 is then hooked over the top of and dropped behind the belt 48. The cover is then revolved to the closed position and the pins 26 and 27 are then inserted in holes 34 and 36, through the belt 48, and then through the holes 35 and 37, in the belt hook to bring the hook 25 around the stud 20. The nuts 21 and 22 are then tightened down on the studs 19 and 20. A watertight seal is then formed between the cover 23, the gasket 29, and the edge portion of the opening 18. The swimmer can then engage in water sports without fear of losing the case or of wetting the cigarettes or matches.

To open the case the nuts 21 and 22 are loos-

ened on the studs 19 and 20 and the cover 23 is lifted on the stud 19 and revolved from over the opening 18. This action tightens the string 43 and pulls up the partition 38 which in turn pulls up the false bottoms 41 and 42, to raise the upper ends of cigarettes 44 and matches 46 above the opening 18 to a position where they are readily accessible. At the same time the case is released from its pinned connection with the belt 48 and can be moved.

While I have herein shown and described my invention in one form, it is obvious that structural changes may be employed without departing from the spirit of the invention, and I therefore do not desire to be limited to this precise form beyond the limitations which may be imposed by the following claim.

I claim:

A water-tight case comprising a container having vertically disposed interior side walls and a top opening, said side walls having two opposed vertical grooves therein; a cover revolvable horizontally over said opening; a horizontally disposed pin carried by said cover; an inverted U-shaped hook carried by said container, said hook having holes in the front and rear portions thereof for receiving the pin; a movable member slideable in the vertical grooves in the side walls of the container; a false bottom connected to said movable member; and means actuated by rotation of the cover from a closed position for raising the vertical member in the grooves.

ELMER CLAMPITT.
